Specification of Letters Patent. Patented Dec. 28, 1920.

Application filed March 2, 1917, Serial No. 152,149. Renewed May 20, 1920. Serial No. 382,927.

To all whom it may concern:

Be it known that we, BERTRAM C. CANDEE and FRANK MOESER, citizens of the United States, residing at Buffalo, in the county of Erie and State of New York, have invented new and useful Improvements in Fuses, of which the following is a specification.

This invention relates to a fuse which is capable of being refilled when the fusible link is melted by the passage of any excessive current over the line in which the fuse is arranged.

The object of this invention is to provide a fuse of this character containing no loose pieces which are liable to get out of order, which has superior means for positively locking the fuse link in its operative position, which is so designed that the same must be closed before it can be inserted in a fuse block and which is so constructed that neither sparks nor flames can escape from the fuse and endanger the surroundings when the fuse blows out.

In the accompanying drawings:

Figure 1 is a longitudinal section of one form of fuse constructed in accordance with our improvements, the section being taken to show the flat sides of the fuse link and the terminals or poles. Fig. 2 is a similar view taken at right angles to Fig. 1. Figs. 3, 4 and 5 are cross sections taken on the correspondingly numbered lines in Figs. 1 and 2. Fig. 6 is a longitudinal section of a fuse containing our invention in a somewhat different form from that disclosed in Figs. 1-5, and also showing the fuse closed. Fig. 7 is a similar view showing the fuse open. Figs. 8 and 9 are cross sections taken on lines 8-8 and 9-9, Fig. 6, respectively.

Similar characters of reference indicate corresponding parts throughout the several views.

The inclosing casing of the fuse shown in Figs. 1-5, preferably comprises an inner tubular section or body 1 which is provided in its side with an inlet opening 2 through which the fuse link 3 is introduced into the casing, and an outer tubular section or cover 4 which is slidable lengthwise on the inner casing section for the purpose of either covering the opening 2 or uncovering the same.

Both of these casing sections are constructed of insulating material such as fiber or the like.

The opposite ends of the inner casing section or body are closed by means of front and rear heads 5, 5^a arranged in these ends, each of these heads being preferably constructed of a pair of inner and outer sheet metal cups 6, 7 which have their flanges telescoping one over the other so that the concave sides of these cups face each other and the disks thereof are spaced apart and form a hollow head, as best shown in Fig. 2.

In its closed position the cover section of the casing has its rear end 8 arranged flush with the corresponding rear end of the inner body section while its front end 9 is arranged beyond the opening in the body section but short of the front end of the latter. Surrounding the front end of the body section of the casing in front of the cover section is a filling ring or sleeve 10 of fiber or similar material which is equal in thickness to the cover section and practically forms an extension at the front end of the latter when the same is in its closed position, as shown in Figs. 1 and 2.

11, 12 represent two metal caps applied to opposite ends of the inclosing casing, the disk of the rear cap 12 extending across the outer ends of the cover and body sections and the rear metal head 7 while its flange surrounds the rear end of the cover section, and the front cap 11 extending with its disk across the outer ends of the filling ring 10 and the adjacent end of the body section and the front head 6, as shown in Figs. 1 and 2. The rear cap 12 is secured to the rear end of the cover so as to move therewith, this connection being preferably effected by means of screws 13 passing transversely through these parts, as shown in Figs. 1 and 5. The front cap is secured to the filling ring, the body section and the front head of the casing by means of screws 14 passing transversely through these parts, as shown in Figs. 1 and 3.

In order to prevent the cover section of the casing from being wholly detached from the body section a stop device is provided which preferably consists of two stop blocks

15, 15 secured to the inner side of the cover within the inlet opening 2 of the body section and adapted in the opened position of the cover to engage with the rear end of the 5 wall of this opening and thereby prevent the cover from being detached from the body section. The inward or forward movement of the cover section is limited by engagement of the disk of the rear cap 10 with the adjacent rear end of the body section, also by engagement of the front end of the cover section with the filling ring and also by engagement of the stop blocks 15 with the front end of the wall of the inlet 15 opening in the body section, as shown in Fig. 1. The stop blocks are preferably arranged on diametrically opposite sides of the cover section and may be secured thereto by means of rivets 16, as shown in Fig. 1, 20 or by any other suitable means.

17, 18 represent the two poles or terminals of the fuse which are preferably constructed of flat metal such as copper. These two poles are arranged lengthwise in correspondingly shaped slots 19, 20 formed in the 25 metal heads and the caps at opposite ends of the fuse casing so that each of these poles or terminals has an outer end arranged outside of the casing for attachment with the 30 clips of a fuse block and an inner end which is arranged within the casing and adapted to receive one end of the fuse link. These poles or terminals may be secured to the respective heads of the inner or body section 35 by any suitable means but preferably by means of metal cross bars 21, 22 arranged within the respective hollow heads and each connected with its central part to the respective terminal by means of a rivet 23 while 40 its opposite ends are provided with laterally projecting lugs 24 which engage with notches 24^a in the opposite edges of the respective pole and are secured to the inner side of the respective hollow metal head. 45 The lugs of the cross bar 21 are held in place on the front head 6 by the same screws 14 which connect this head with the casing body, filling ring and the front cap, while the lugs of the rear cross bar 22 are connected with the rear head 7 and the rear 50 end of the body section by means of screws 25 passing transversely through these parts, as shown in Figs. 1 and 5.

The poles or terminals are intended to be 55 fitted fairly snug in the openings formed in the metal heads and caps at opposite ends of the casing sections but to guard against the passage of any flames outwardly through these openings when the fuse link melts or 60 blows out each of the hollow heads is preferably filled with asbestos 26, as shown in Figs. 2, 3 and 5, or similar non-combustible or heat insulating material.

The fuse link may be attached to the 65 inner ends of the poles or terminals by any

suitable means but the means which are shown in the drawings are preferred and constructed as follows:

27 represents a longitudinal slit formed in the inner end of each pole or terminal and 70 dividing the same into a pair of clamping jaws 28, 29 which are adapted to engage with opposite sides of one end of the fuse link. Embracing the clamping jaws of each pole is a transverse yoke which comprises 75 two parallel arms 30 engaging with notches 31 formed in opposite edges of the clamping jaws, two inwardly off-set portions 32 on the lower ends of the arms and forming shoulders which engage with the underside of the 80 lower jaw of the pole and a V-shaped brace 33 extending outwardly from the inner ends of said off-set portions and bearing against the adjacent part of the inner side of the body section, as shown in Figs. 2 and 4. 85 The upper ends of the arms of the yoke are connected by a pin or rivet 34 which extends across the top of the upper clamping jaw of the pole. On this pin is pivotally mounted an eccentric 35 which is provided with a 90 laterally projecting handle or finger piece 36. Between the face of this eccentric and the upper clamping jaw is arranged a wearing piece or strip 37 which is held in place by providing its opposite ends with notches 95 38 which receive the adjacent arms of the yoke. Upon turning the eccentric so that the low part of its face is arranged opposite the clamping jaws the latter by their resilience will be loosened sufficiently to permit 100 one end of the fuse link to be freely inserted between the same and upon subsequently turning this eccentric so that the high part of its face is opposite the clamping jaws then the latter will be pressed together and grip the fuse link sufficiently firm to produce a good contact. The wearing piece is preferably constructed of steel or other hard material so as to save the 105 pole, which is usually made of copper or 110 similar material, from rapid wear.

The fuse link may be introduced through the inlet opening of the body section and secured to the pole while the cover section is moved lengthwise and backwardly relatively to the body section a sufficient distance to uncover the inlet of the casing. When thus withdrawn the cover section 115 encloses the outer attaching end of the rear pole or terminal and thereby renders it impossible to apply this fuse to the clips of a fuse block. In order therefore to permit of attaching the outer ends of the poles to the 120 clips of a fuse block it is necessary to first move the cover section forwardly on the 125 body section until the inlet opening of the latter is completely closed, thereby preventing use of the fuse in the fuse block until the casing for the fuse link has been completely closed, thus insuring against acci- 120

dents in the event that the fuse link burns out or melts.

The modified form of fuse shown in Figs. 6-9 of our invention is constructed as follows:

39 represents the inner tubular body section of the casing which is provided in its sides with two longitudinal slots or inlet openings 40. 41 represents the outer tubular cover section which is adapted to be moved lengthwise relatively to the inner or body section for the purpose of covering or uncovering said inlet openings. Both of these sections of the casing are constructed 15 of fiber or similar electric insulating material. In opposite ends of the body section are arranged metal heads 42, 43 which are secured thereto by means of transverse screws 44, 45. Each of these heads is provided with a longitudinal slit 46 extending outwardly from its inner face and diametrically across the respective head so that a fuse link 47 may be passed inwardly through the opening 40 of the body section and between 20 the jaws 48, 48 formed on each of the heads between the slit therein. After the ends of the fuse link have been thus inserted between the jaws of the heads these jaws may be drawn tightly against opposite sides of 25 the fuse link by means of the same screws 44, 45 which connect these heads with the body section of the casing.

49, 50 represent two metal caps arranged at opposite ends of the casing, the disk of 35 the front cap 49 extending across the front end of the body section and the front head of the casing and having its flange overlapping the front end of the cover section in the closed position of the latter. This front 40 cap is provided in its disk with a central screw threaded opening 51 which receives a screw threaded boss 52 on the outer end of the front head and is held against turning thereon after the same has been assembled 45 by means of brazing or soldering 53 or the like. The flange of this front cap is also provided with an opening 54 in line with the head of the screw 44 so as to permit the latter to be turned by means of a screw driver 50 when the cover section is withdrawn. The rear cap 50 extends with its disk across the rear end of the cover section and the adjacent ends of the body section and rear head while its flange surrounds the rear part of 55 the cover section. The disk of the rear cap is provided centrally with a screw threaded opening 55 which is adapted to engage with a screw threaded boss 56 on the outer side of the rear casing head in the assembled position of the parts and thereby hold the cover 60 section in its closed position in which it extends over the inlet openings in the body section and prevents any flames due to the melting or burning of the fuse link from 65 reaching the exterior of the fuse and setting

fire to anything which may be adjacent thereto. Complete withdrawal of the cover section of the casing from the body section thereof is prevented by means of a stop pin 57 arranged on the inner side of the front 70 end of the cover section and adapted to engage with the rear end 58 of a longitudinal groove 59 formed in the adjacent part of the outer side of the body section, as shown in Fig. 7. In order to retain the rear cap 50 on the cover section and still permit the same to be turned for screwing it on to the rear boss of the rear head the inner end of the flange of this cap is provided with an inwardly turned rim 60 which engages with a 75 circumferential groove 61 in the adjacent part of the periphery of the cover section, as shown in Figs. 6 and 7. By this means all of the several parts of the fuse are 80 permanently connected with each other but are 85 free to move the requisite extent for re-filling the fuse with new fuse links from time to time when required.

In the construction of the fuse shown in Figs. 6-9, the metal caps form the terminals or poles of the fuse which are adapted to engage with the clips of a fuse block and in this construction it also becomes necessary to fully close the cover section over the inlet openings in the body section before the 90 cap-shaped poles are in a position to properly engage the clips of the fuse block, thereby insuring complete inclosure of the fuse link and guarding against accidents by fire when the same is in condition to be properly 95 used.

We claim as our invention:

1. A fuse comprising an inner tubular casing section provided with an inlet opening in its side for the passage of a fuse link, 105 an outer tubular casing section slideable lengthwise on said inner section, terminals adapted to be connected with said fuse link and to be engaged with a fuse block, and means for limiting the sliding movement of 110 said casing sections relatively to one another.

2. A fuse comprising an inner tubular casing section provided with an inlet opening in its side for the passage of a fuse link, 115 an outer tubular casing section slideable lengthwise on said inner section, terminals adapted to be connected with said fuse link and to be engaged with a fuse block, and means for limiting the sliding movement of 120 said casing sections relatively to one another comprising a block arranged on the inner side of said outer casing section and adapted to engage with the wall of the opening in said inner casing section.

3. A fuse comprising an inner tubular casing section having an opening in its side for the passage of a fuse link, an outer tubular casing section slideable lengthwise on said inner section, hollow heads arranged in 130

opposite ends of said inner casing section and each composed of two cup-shaped sections which telescope with their concave sides facing each other, and terminals 5 mounted on said heads and adapted to be connected with a fuse link and a fuse block.

4. A fuse comprising an inner tubular casing section having an opening in its side for the passage of a fuse link, an outer 10 tubular casing section slideable lengthwise on said inner section, hollow heads arranged in opposite ends of said inner casing section and each composed of two cup-shaped sections which telescope with their 15 concave sides facing each other and which are provided with slots, and terminals arranged in the slots of said heads and adapted to be connected with a fuse link and a fuse block.

20 5. A fuse comprising an inner tubular casing section having an opening in its side for the passage of a fuse link, an outer tubular casing section slideable lengthwise on said inner section, hollow heads arranged 25 in opposite ends of said inner casing section and each composed of two cup-shaped sections which telescope with their concave sides facing each other and which are provided with slots, terminals arranged in the 30 slots of said heads and adapted to be connected with a fuse link and a fuse block and each provided on its opposite edges within its companion head with notches, and cross bars arranged in said heads and each connected with the respective terminal and provided at its opposite ends with lugs which are arranged in said notches of the terminals 35 and are connected with the adjacent head.

6. A fuse comprising an inner tubular 40 casing section having an opening in its side for the passage of a fuse link, an outer tubular casing section slideable lengthwise on said inner section, hollow heads arranged in opposite ends of said inner casing section 45 and each composed of two cup-shaped sections which telescope with their concave sides facing each other and which are provided with slots, an insulating filling arranged with each of said heads, and terminals arranged in the slots of said heads 50 and adapted to be connected with a fuse link and a fuse block.

7. A fuse comprising an inner tubular casing section having an opening in its side 55 for the passage of a fuse link, an outer tubular casing section slideable lengthwise on said inner section, hollow heads arranged in opposite ends of said inner casing section and each composed of two cup-shaped sections 60 which telescope with their concave sides facing each other and which are provided with slots, terminals arranged in the slots of said heads and adapted to be connected with a fuse link and a fuse block, and cross bars ar-

ranged in said heads, respectively, and each 65 connected centrally with the adjacent terminal and at its ends with the companion head.

8. A fuse comprising an inner tubular casing section having an opening in its side for the passage of a fuse link, an outer tubular casing section slideable lengthwise on said inner section, hollow heads arranged in opposite ends of said inner casing section and each composed of two cup-shaped sections 75 which telescope with their concave sides facing each other and which are provided with slots, terminals arranged in the slots of said heads and adapted to be connected with a fuse link and a fuse block, and cross bars arranged in said heads, respectively, and each connected centrally with the adjacent terminal and provided at its ends with lugs which are connected with the inner side of 80 the companion head.

9. A fuse comprising an inner tubular casing section having an inlet opening in its side for the passage of a fuse link, an outer tubular casing section slideable lengthwise on the inner casing section, heads arranged 90 in opposite ends of said inner casing section, terminals arranged in said heads and adapted to be connected with a fuse link and with a fuse block, caps applied to opposite ends of said casing sections and having openings 95 through which said terminals project, one of said caps being connected with the inner casing section and the other with the outer casing section, and a filling ring arranged between the inner casing section and the cap 100 attached thereto and in line with the outer casing section.

10. A fuse comprising a casing, terminals arranged in the ends of the casing and each terminal provided at its inner end with two jaws which are adapted to grip a fuse link between them, and means for pressing the jaws of each terminal together comprising a yoke having two parallel arms engaging with notches in opposite edges of the respective terminal, off-sets at one end of said arms and engaging with the outer side of one jaw of a pair and a brace connecting said off-sets and bearing against the inner side of said inner casing section, a pin mounted transversely on the opposite ends of said arms, and an eccentric mounted on said pin and adapted to press against the outer side of the outer jaw.

11. A fuse comprising a casing, terminals arranged in the ends of the casing and each terminal provided at its inner end with two jaws which are adapted to grip a fuse link between them, and means for pressing the jaws of each terminal together comprising 120 a yoke having two parallel arms engaging with notches in opposite edges of the respective terminal, off-sets at one end of said arms 115 and engaging with the outer side of one jaw of a pair and a brace connecting said off-sets and bearing against the inner side of said inner casing section, a pin mounted transversely on the opposite ends of said arms, and an eccentric mounted on said pin and adapted to press against the outer side of the outer jaw.

and engaging with the outer side of one jaw of a pair and a brace connecting said off-sets and bearing against the inner side of said inner casing section, a pin mounted transversely on the opposite ends of said arms, an eccentric mounted on said pin and adapted to press against the outer side of the other jaw and a wearing plate arranged between the eccentric and the adjacent jaw and provided at its ends with notches which receive the arms of said yoke.
